(57) CLAIM

The ornamental design for the board, as shown and described.

DESCRIPTION

FIG. 1 is a front view of the board showing my new design;
FIG. 2 is a back view thereof;
FIG. 3 is a first side view thereof;
FIG. 4 is a second side view thereof;
FIG. 5 is a top plan view thereof;
FIG. 6 is a bottom plan view thereof; and,
FIG. 7 is a perspective view thereof.

The broken lines in the drawings illustrate the portions of the design that form no part of the claim.
